APPARATUS FOR FORMING NITROGEN
OXIDESFredrik W. de Jahn, New York, N. Y., assignor to
Frank A. Bower, Bayside, N. Y.Application April 25, 1928, Serial No. 272,618
Renewed December 29, 1932

4 Claims. (Cl. 23—288)

This invention relates to the manufacture of oxides of nitrogen, and more particularly to the manufacture of nitric acid by oxidizing of ammonia gas.

- 5 The oxidation of ammonia takes place at high temperatures and involves a large amount of heat, and I have found that it is advantageous to lower the temperature of the gases as soon as possible after oxidation.
- 10 The object of my invention is to provide a simple and durable apparatus for the oxidation of the ammonia and the immediate reduction of its temperature.

15 Further objects of the invention in the structural details of the apparatus and its use to pre-heat the air for the oxidizing will appear from the following description taken in connection with the accompanying drawing, in which

20 Fig. 1 is a diagrammatic elevational view of the apparatus.

Fig. 2 is a partial vertical sectional view of the oxidizing chamber.

Fig. 3 is a vertical cross sectional view on the line 3—3 of Fig. 2, and

25 Fig. 4 is an enlarged sectional view of a portion of Fig. 2.

In the apparatus illustrated in the drawing the ammonia gas is supplied through the pipe 6 to the mixing nozzle 6, receiving its supply of air through the pipe 7 and passing it in jet form into the right-hand end of the oxidizing chamber designated generally at 8 and against the platinum gauze 9 forming a diaphragm across the chamber adjacent its entrance end. The oxidation taking place in the neighborhood of the gauze 9 develops a large amount of heat and therefore the generally cylindrical shell 10 is lined its full length with a material 11 of high insulating characteristics, such as silocell. At the right hand end of the shell 10 the lining 11 is thinned out to approximately half its thickness for the reception of a flanged bracket 12 which extends inwardly within the shell forming a removable supporting structure for the gauze 9. The oxidizing chamber 8 between the gauze 9 and its right hand end is lined with a refractory material placed therein and fitted within the bracket in sectional rings 13 which are preferably of dust proof material such as isolantite so as to avoid clogging of the platinum gauze 9. The hot gases from the gauze 9 pass outward through the opening 14 to the nitric acid absorption apparatus and the main object of this invention is to provide for the lowering of the temperature of these gases in the most efficient manner.

For this purpose the end of the shell 10 is provided with a header 15 and diaphragm 16 connected to pipes adapted to carry air or other gas into the oxidizing space and close to the gauze 9. The diaphragm 16 has set into it a system of U-shaped pipes 20, each pipe extending from the upper portion of the diaphragm to a downward bend positioned adjacent the gauze 9 and then back to an opening in the lower portion of the diaphragm. The header 15 is provided with an entrance port space 21 and a discharge port space 22 separated by an intermediate baffle 23 so that air entering through piping 24 will pass through the U-pipes 20 and then out through port 22 and piping 7 to the mixing nozzle 6, the U-shaped pipes being of varying lengths of corresponding inside diameters so as to present the same resistance to the flow of the gases, this in order that the flow of gases may be uniform through all the pipes. In this way the cooling of the hot gases from the gauze 9 is used to pre-heat the air or other gas used for the oxidizing process.

The material used for the shell and other portions of the structure is preferably chromium alloy such as ascolay, the shell parts being preferably of sheet material, as indicated, with welded joints to the surrounding ring flanges.

The bracket 12 carrying the gauze 9 is a separable gauze unit insertable within the shell 10 insulated therefrom by the lining 11. The gauze 9 is placed between the rings 25, 26 carried by the bracket 12. The rings 25, 26 with the gauze 9 therebetween are held together in assembled relation and clamped to the extension 27 of the bracket 12 by means of clamping bolts 28 passing through the rings and threaded into the extension 27. The ring 25 is provided with diametrically opposite elongated apertures 29 for the spaced silica rods 30 which form a brace for the gauze 9 in the direction opposite to the entering jet from the nozzle 6 preventing any bulging of the gauze toward the pipes 20.

The gauze unit is held in position within the shell 10 between end flange ring 31 secured to the outer end of the shell and the outer flange of the end header 32 by means of clamping bolts 33 which pass through the end flange ring 31 the bracket flange 34 of the bracket 12 and the outer flange of the header 32, suitable gaskets being inserted therebetween. The gauze unit may thus be inspected, removed or replaced simply by separating the header 32 from the flange ring 31 and this also gives complete access to the entire

- interior of the oxidizing chamber. The header plate 15 and its diaphragm or tube sheet 16 are also removably attached by bolts 35 to the end flange ring 36 so that the whole shell construction can be readily dismantled from either end. If desired, baffle partitions may be inserted between the gauze 9 and the outlet 14, these baffles being provided with tube openings leaving an annular orifice around the cooling tubes through which the hot gases are forced into close contact with the cooling tubes. This construction may be used at atmospheric pressure, and is particularly advantageous when working with higher pressure.
- 15 The header is also provided with an enlarged section 37 having an opening over which is an observation cover 39 in which is placed an observation window 38 clamped to the enlarged section by means of clamping bolts 40. This window is so situated that the entire gauze 9 can be observed to see that it is functioning properly.
- In starting the operation and to properly ignite the gases an igniting system is inserted through the header 32 consisting of a hydrogen or other gas inlet tube 41 and an electric terminal 42 terminating within the chamber 8. One side of the electric circuit is grounded on the apparatus and the other side connected to the terminal 42 so that a spark from the terminal 42 jumps across the spark gap 43 between the end of the terminal 42 and the end of the tube 41.
- In the apparatus of this invention the hot freshly formed oxides are immediately cooled so as to avoid the effect of hot temperature in breaking down the compounds formed by the burning. This maintains or increases the final yield of the desired oxides. At the same time the rapid cooling minimizes the high temperature effects and avoids the complications necessary in handling these very hot gases which burn at a temperature of about 900° C. and are quickly cooled in the apparatus of this invention to a temperature in the neighborhood of 550 to 600° C. by the gases forced at a rapid rate through the tubes 29. The U-shaped cooling tubes are free to expand and contract under the temperature changes without imposing any strains upon the shell or other parts, and at the same time within the relatively small shell space they afford a very large and efficient cooling area. The structure of this invention thus provides a very simple efficient and

compact cooling means maintaining the composition of the gases as formed and avoiding the large cumbersome special cooling chambers of the prior art.

I claim:

1. In apparatus for forming nitrogen oxide the combination with an inlet for ammonia gas and an inlet for an oxidizing gas, of combining means therefor comprising a shell forming a combining chamber, a metal gauze within said shell, a supporting bracket for said gauze having a section extending within said shell, heat insulating means for insulating said section and its point of attachment to said gauze from said shell and from said combining chamber. 5

10 2. In apparatus for forming nitrogen oxides the combination with an inlet for ammonia gas and an inlet for an oxidizing gas of combining means therefor comprising a metal gauze unit adapted to form nitrogen oxides of high temperature, a shell forming a combining chamber and cooling tubes supported at one end of said shell in close proximity to said gauze to cool said oxides upon their formation, said gauze unit extending into said shell and detachably supported to the opposite end portion of said shell. 15

20 3. In apparatus for forming nitrogen oxides the combination with an inlet for ammonia gas and an inlet for an oxidizing gas of combining means therefor comprising a metal gauze within said shell, a supporting bracket for said gauze one end of which is attached to said gauze and the opposite end of said bracket to the end of said shell at its exterior, igniting means within said combining chamber, means for observing said gauze from the exterior of said shell and cooling means within said shell to cool said oxides immediately upon their formation. 25

30 4. In apparatus for forming nitrogen oxides the combination with an inlet for ammonia gas and an inlet for an oxidizing gas of combining means therefor comprising a shell forming a combining chamber, a metal gauze unit attached to one end of said shell and extending therein adapted to form nitrogen oxides of high temperature, insulating means extending the entire length of the interior of said shell having a cut-away section at one end in which said gauze unit is located and insulating means within the interior of said gauze unit. 35 40 45
